Specification for Design.

Patented Jan. 17, 1922.

Application filed April 26, 1920. Serial No. 376,871. Term of patent 7 years.

To all whom it may concern:

Be it known that I, RICHARD A. FINIS, a citizen of the United States, residing at 1616 Jackson St., in the city and county of San Francisco and State of California, have invented a certain new, original, and ornamental Design for a Motor-Vehicle Signal, of which the following is a specification, reference being had to the accompanying drawing, forming a part thereof.

Fig. 1 is a face view of the device.

Fig. 2 is an interior view, the face being opened downwardly.

The casing and the letters are to be opaque, while the panels are to be of translucent material, suitably colored.

I claim:

The ornamental design for a motor vehicle signal, as shown.

RICHARD A. FINIS.
